UNITED STATES PATENT OFFICE.

HENRY MIKEL BARR, OF WADSWORTH, NEVADA.

TUBE-EXPANDER.

SPECIFICATION forming part of Letters Patent No. 707,292, dated August 19, 1902.

Application filed March 27, 1902. Serial No. 100,181. (No model.)

To all whom it may concern:

Be it known that I, HENRY MIKEL BARR, a citizen of the United States, residing at Wadsworth, county of Washoe, State of Nevada, 5 have invented an Improvement in Tube-Expanders; and I hereby declare the following to be a full, clear, and exact description of the same.

My invention relates to improvements in devices for expanding the ends of flues in boiler-sheets. Its object is to provide a rolling-tool which will be simple in construction and which will automatically release itself from the tube after spreading the latter, there- 15 by enabling the operator to roll all flues exactly alike.

It consists of a casing embracing revoluble rollers, a mandrel or spreader, a sleeve having a left-hand screw-thread turnable in the 20 casing and against which the mandrel is adapted to abut as it is driven home, and a gage-plate disposed in relation to the sleeve.

It also comprises details which will be more fully set forth hereinafter, having reference 25 to the accompanying drawings, in which—

Figure 1 is an exterior view of my invention. Fig. 2 is a longitudinal section of the casing. Fig. 3 is a transverse section on the line $x-x$, Fig. 2. Fig. 4 is a view of the mandrel with the sleeve in section.

A represents a suitable casing carrying at its forward end the usual rollers 2 and operated by a tapered mandrel or spreader 3. A sleeve 4, having a left-handed thread, screws 35 into the rear end of the casing, and the distance which the head of the sleeve is desired to project beyond the casing may be determined by means of a slidable gage-plate 5. The sleeve is provided with a left-hand thread 40 for the reason that it is customary to turn the mandrel to the right as it is advanced. The head of the sleeve has a central polygonal recess 6, into which a like-shaped projection 7 on the mandrel is adapted to fit when the 45 mandrel is inserted into the sleeve. The end of the mandrel is made polygonal in cross-section either to receive a wrench or the socket of a pneumatic tool.

In operation the roller end of the tool is 50 placed in the end of a tube the desired distance. The mandrel is inserted into the sleeve and casing and power applied to drive

in and rotate the mandrel. Having determined at what distance the mandrel must be driven in to spread one of any given set of 55 tubes properly, the gage 5 and sleeve 4 are set accordingly, so that as the mandrel advances and the projection 7 engages the recess 6 the sleeve will be turned to automatically retract the mandrel. When the mandrel is released by the action of the sleeve, 60 the tool can be removed by hand. Heretofore it has been necessary to use a hammer to loosen the mandrel after spreading a flue. Thus not only is a considerable saving of 65 time effected, but all tubes may be expanded uniformly, whereas with the ordinary rolling-tool it has been entirely a matter of judgment of the operator when to stop rolling any particular tube.

In the operation of these tools the mandrel is alternately struck by a hammer or like implement and turned by a wrench or other suitable means. The blows serve to advance the mandrel step by step to spread the rollers, and the turning is for the purpose of rolling the tube evenly. It is not to be understood that the part 7 of the mandrel would engage the socket 6 by merely turning the mandrel. The mandrel is advanced, say, one-fourth of an inch at a blow, and is then turned. It is given another tap and turned again, and so on until the part 7 comes up to the socket. Sufficient care is taken to bring the sides of the shoulder and socket into line, and the 85 next blow drives the mandrel in sufficiently, so that the next time the latter is turned to operate the rollers it will also turn the sleeve 4 and gradually withdraw the mandrel. In actual practice the corners of the shoulder of 90 the part 7 are slightly rounded, and the edges of socket are beveled outwardly to insure the shoulder entering easily.

Having thus described my invention, what I claim, and desire to secure by Letters Pat- 95 ent, is—

1. The combination in a flue-expander, of a casing, a tubular series of rods, a mandrel, and means in connection with said casing by which the mandrel may be automatically re- 100 tracted.

2. The combination in a flue-expander, of a casing, a tubular series of rods, a mandrel, means by which the inward movement of said

mandrel may be limited and means by which said mandrel may be retracted automatically.

3. The combination in a flue-expander, of a casing, revoluble rods carried thereby, a spreader, stop means upon the casing by which the inward movement of the spreader is limited and means by which the spreader is retracted automatically on engaging said stop.

10 4. The combination in a flue-expander, of a casing, rollers carried thereby, a left-threaded sleeve concentric with said casing and a mandrel adapted to be inserted through said sleeve and casing.

15 5. The combination in a flue-expander, of a casing, rollers thereon, a sleeve provided with left threads and turnable in said casing and concentric therewith, and a mandrel adapted to be inserted in said sleeve and cas-

20 ing to spread the rollers.

6. The combination in a flue-expander, of a casing, rollers thereon, a sleeve threaded and turnable in said casing, a mandrel, and engaging stop, means upon the mandrel and

sleeve whereby the mandrel is retracted as it 25 is turned in opposition to the threads on the sleeve.

7. The combination in a tube-expander, of a casing, rollers thereon, a mandrel, a left-threaded sleeve in said casing and turnable 30 in opposition to the mandrel, and an adjustable gage-plate in relation to said sleeve.

8. The combination in a tube-expander, of a casing, rollers thereon, a mandrel, a sleeve having a left-hand thread and in which said 35 mandrel is slideable, a recess in the head of said sleeve, a projection on the mandrel adapted to engage said recess to turn the sleeve and retract the mandrel, and a gage-plate slideable upon the casing and engaging 40 the sleeve.

In witness whereof I have hereunto set my hand.

HENRY MIKEL BARR.
